UNITED STATES PATENT OFFICE.

JOHN M. CULVER, OF WALLINGFORD, CONNECTICUT, ASSIGNOR TO
WALLACE BROTHERS, OF SAME PLACE.

DESIGN FOR SPOON.

Specification forming part of Design No. **11,510**, dated November 18, 1879; application filed October 23, 1879
[Term of patent 7 years.]

To all whom it may concern:

Be it known that I, JOHN M. CULVER, of Wallingford, in the county of New Haven and State of Connecticut, have invented a new Design for Spoons; and I do hereby declare the following, when taken in connection with the accompanying drawing and the letters of reference marked thereon, to be a full, clear, and exact description of the same, which said drawing constitutes part of this specification, and represents a face view.

This invention relates to a design for the handle of spoons, forks, and similar articles; and the design consists in the ornamentation of the handle, as shown in the accompanying illustration.

The outline or shape of the handle is common and well known—that is, lancet-shaped tip, thence gradually contracting to near the bowl, then expanding and running into the edge of the bowl.

The face has a spirally-curved ornamented

band, *a*, running from one edge to the other. Below this band, at the narrow part of the handle, is a boss, *b*, and below this boss, at the point where the handle begins to expand, is a second, boss, *c*. The surface between the two bosses *b c* is reeded longitudinally. From the upper boss a floriated vine springs and runs up the surface, apparently behind the band, onto the surface above, all as shown in the accompanying illustration.

I claim—

The herein-described design for ornamentation of spoon-handles, consisting of the spirally-curved band *a*, bosses *b c* below, reeded surface between said bosses, and floriated vine running from the boss *b* up onto the surface above the band, all as shown in the accompanying illustration.

JOHN M. CULVER.
